UNITED STATES PATENT OFFICE

2,503,656

CORN PAD

William M. Cone, Atlanta, Ga., assignor of one-third to Lois D. Cone, Atlanta, Ga.

Application February 3, 1949, Serial No. 74,308

2 Claims. (Cl. 128—153)

1

This invention relates to a corn pad of novel construction and design to be employed as an inside pad, the primary purpose of which is to receive and cushion corns on the toes and webs of the foot.

An important object of this invention is to provide a corn pad of particular design and construction which will cradle and elevate slightly one of the toes to prevent friction between joints and friction between adjacent corns while the corns are properly received in and cushioned by the pads.

A further object of this invention is to provide a corn pad of the character described which is fabricated of a porous resilient material, such as air foam rubber, which allows the free circulation of air between the toes further helping to cure the corn and also assisting in the treatment of cracks and fissures in the web of the toes caused by athlete's foot or other fungus growths.

The applicant is aware of the existence of corn pads having elongated grooves on the opposite side walls of the pad for cradling and elevating adjacent toes. These pads are used merely as separators and allow the adjacent joints or adjacent corns of the toes to stay exactly opposite each other even though they remain elevated. Thus, the adjacent joints or adjacent corns will still rub against each other despite these pads if the shoe is somewhat tight. The device of the instant invention provides a pad in the form of an elongated body having spaced longitudinal walls, only one side of which includes an elongated groove, the other side remaining planar or flat. This construction permits only one of the toes to be slightly elevated and cradled while the toe adjacent the flat side remains depressed and rests upon the inner sole of the shoe. Thus, any possible friction between adjacent joints or adjacent corns is eliminated because these joints or corns are out of alignment.

These, together with various ancillary objects and features of the invention which will later become apparent as the following description proceeds, are attained by the device, a preferred embodiment of which has been illustrated, by way of example only, in the accompanying drawings, wherein:

Figure 1 is a perspective view of the corn pads of the instant invention as applied between toes of a foot;

Figure 2 is a transverse vertical sectional view through the device as shown in Figure 1, the foot being received in a shoe shown in section;

Figure 3 is a side elevational view of one modification of the corn pad;

2

Figure 4 is a sectional view taken substantially on the plane of section line 4—4 of Figure 3; and Figure 5 is a side elevational view of another modification of the corn pad.

Specific reference will now be made to the drawings. In the several views, in the accompanying drawings and in the following specification, similar reference characters indicate corresponding elements throughout.

10 Indicated generally at 10 is a foot having the usual toes 12 separated by webs 14. The corn pads 16 of the instant invention are, as shown clearly in Figures 1 and 2, interposable between adjacent toes 18 and 20 and 22 and 24.

15 Whenever a corn found in a web 14 of the foot is to be treated, the construction and design of the corn pad shown in Figure 5 is employed. This consists of an elongated body of resilient porous material, such as air foam rubber having longitudinally extending spaced sides 26 and 28 having

20 a rear face 30 and a front face 32 arcuated to conform to the toe portion of a shoe 34. The side 26 of the elongated body is provided with an elongated groove 36, preferably concaved, for cradling the toe 18. As will be seen clearly from Figure 2, when the toe 18 is cradled, it is slightly elevated from the inner sole 38 of the shoe. The rear face 30 of the elongated body 16 is further provided with a vertical groove 40, preferably concaved, for receiving and cushioning the corn (not shown) found in the web portion 14 of the foot 10. Thus, it will be seen that while the toe 18 is slightly elevated from the inner sole 38, the adjacent toe 20 abutting the planar or flat opposite side 28 of the elongated body is depressed and rests upon the inner sole 38. In such a position, the adjacent joints of the toes 18 and 20 are prevented from rubbing against each other no matter how tight the shoe 34 fits about the foot 10.

25 The modified corn pad shown at 42 is employed in conjunction with corns 44 on the sides of the toes and is similar in construction and design to the corn pad 16. This modified corn pad consists also of an elongated resilient porous body having spaced longitudinal sides 46 and 48, a rear face 50 and a front arcuated face 52 shaped to conform to the inner contour of the toe portion of the shoe 34.

30 The rear face 50 of the body 42 is further provided with a vertical groove 54, preferably concave, for receiving either a corn in the web 14 of the foot or for receiving the web itself. One side 46 of the body includes a longitudinal groove 56 for cradling and elevating the toe 22 having the corn 44 thereon. For receiving and cushioning the corn 44 itself, the body 42 is provided with a

transversely extending bore or aperture 58. Thus, it will be seen that the toe 22 is elevated slightly from the inner sole 38 of the shoe while the toe 24 abutting the planar or flat side 48 remains depressed and rests upon the inner sole. In this position, adjacent joints or corns on the toes 22 and 24 cannot possibly rub against each other no matter how tight the shoe is about the toes.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and within the scope of the appended claims.

Having described the invention, what is claimed as new is:

1. An inside corn pad interposable between the toes comprising an elongated porous resilient body having spaced longitudinal sides and a longitudinal groove in one of said sides for cradling

and elevating the toe having a corn thereon to prevent friction of the corn with a corn on an adjacent toe, said body having a transverse aperture therethrough for receiving and cushioning the corn.

2. An inside corn pad interposable between the toes comprising an elongated porous resilient body having spaced longitudinal sides and a longitudinal groove in one of said sides for cradling and elevating the toe having a corn thereon to prevent friction of the corn with a corn on an adjacent toe, and a vertical groove at the rear of said body for receiving and cushioning a corn in the web between the toes, said body having a transverse aperture therethrough for receiving and cushioning the corn.
